UNITED STATES PATENT OFFICE.

WILLIAM A. LUBY, OF KALAMAZOO, MICHIGAN.

AUTOMATIC ELECTRIC BLOCK-SIGNALING.

SPECIFICATION forming part of Letters Patent No. 764,583, dated July 5, 1904.

Application filed May 9, 1903. Serial No. 156,337. (No model.)

To all whom it may concern:

Be it known that I, WILLIAM A. LUBY, a citizen of the United States, residing at the city of Kalamazoo, in the county of Kalamazoo and State of Michigan, have invented certain new and useful Improvements in Automatic Electric Block-Signaling, of which the following is a specification.

My object is to provide an automatic electric block-signaling system for double-track railways which will operate by either an alternating or continuous electric current, which will be actually practical, reasonably simple and inexpensive to construct, economical to operate, sufficiently elastic in principle to perform any function required in block-signaling, and which will facilitate to the utmost instead of interrupting the traffic of a railroad, the main details and means by which my invention is carried into effect being hereinafter fully explained.

Referring to the accompanying drawings, which form a part hereof, and in which like letters and figures of reference refer to similar parts throughout the several views, Figure 1 is a diagrammatic illustration of one full and two partial blocks of my system, showing overlaps. In this view the signal and rail circuits are shown as energized by an alternating electric current from a common source, the same being transformed for the circuits of each block and signal by means of transforming-condensers. Condensers are also shown as connected in parallel with the coils included in the rail-circuit. Fig. 2 is a similar illustration showing a portion of one block in which is shown means for protecting a train against spreading rails, means by which on entering a block a train automatically locks all or any particular switch in advance of it and unlocks them one after another, means for automatically lowering gates at a highway-crossing or giving other warning when a train enters a block and restoring the same when the train passes the highway, and means by which a burned bridge or culvert will set a block at "danger." This figure is designed to be placed between Figs. 1 and 3, the right of the figure to be placed at the left of Fig. 1 and the left 50 of the figure to be placed at the right of Fig.

3. When this is done, it will be seen that the source of energy by which the rails of Fig. 2 are energized is toward the left of the figure, being the transformer shown in Fig. 3. Trains are supposed to move from right to left, as in the other figures. Signal L' is at the incoming end and signal L² at the outgoing end of the block of which Fig. 2 is a part. Fig. 3 is likewise a diagrammatic illustration. It shows the abutting ends of two blocks, the signal and rail circuits being shown as energized by an alternating current, the potential being reduced by means of an ordinary alternating-current transformer. The illustration shows the same electric circuits and connections as appear at the abutting ends of blocks in Fig. 1 and in addition thereto means by which the dangerous condition of a preceding block is communicated to an approaching train, means by which the train receiving such notification automatically whistles as a call for signals, so that if the signal is held at "danger" through the carelessness of workmen their attention may be drawn to the fact and the signal allowed to come to "safety" before stopping the train. There is also shown means for partially setting the brakes and putting the train under control when it first receives the information as to the condition of the block next in advance and means for automatically applying the emergency-brakes and automatically stopping the train if it passes a signal while the block ahead is dangerous. The signals thus communicated to the train and the means for stopping it are entirely independent of the actual condition or position of the signal, the functions being performed whether the signal stands at "danger" or "safety" if the block next in advance is dangerous. There is also shown in this illustration means by which the violation of a signal may be recorded both at the signal and on the train. Fig. 4 is a side elevation of the contact-rail N, showing the insulation Q, which interrupts the constant flow of current and enables the steam-whistle to give any particular number of blasts of short or long duration. Fig. 5 is a diagrammatic illustration in which the rail and signal circuits are shown as energized by a continuous current, one of the signals being 100

shown as operating with and the other as without an overlap.

In the system herein shown the signals stand normally at "danger" by gravity. They are automatically brought to "safety" by an approaching train. The circuit by which a signal is operated is normally open and includes the source of energy S, signal-actuating mechanism M, and two circuit-interrupters A and B, which are controlled by electromagnets included in the normally closed rail-circuits of two abutting blocks. One of the circuit-interrupters A is controlled by the electromagnet D, which is in the rail-circuit at the incoming end of one of the blocks. The other circuit-interrupter B is controlled by the electromagnet C, which is in the rail-circuit and at the outgoing end of an abutting block. The circuit-interrupter A is held normally closed by the electromagnet D, and circuit-interrupter B is held normally open by gravity or other suitable means, the normal current passing through the coil of magnet C not being sufficient to cause it to actuate interrupter B. Magnets C and D are both of low resistance; but magnet D has a resistance preferably eight or ten times greater than magnet C, the greater the better, so long as, considered by itself, it is of very low resistance, preferably not to exceed one-quarter of one ohm. The main object in having coil D D' of greater resistance than coil C C' is to enable coil C' to actuate interrupter B positively when coil D is short-circuited. Instead of having the increased resistance in coil D itself it may be placed in either of the wires ν or α , where it will perform its main function equally well. It is preferred, however, to have the resistance in coil D and to make it by additional convolutions of wire in order to get the advantage of the increased ampere-turns, though each coil by proper adjustments of interrupters A and B would perform the function ascribed to it were the ampere-turns of each the same and the resistance of coil D greater than that of C. The proper adjustment just mentioned would consist of bringing the armature or interrupter A, which is here shown as the armature, within such proximity to its magnet D as to be operated thereby and adjusting the armature or interrupter B', which is shown as acting as an armature, so that it will be sufficiently distant from its magnet C' as not to be operated thereby when coil D is in circuit, but close enough so that it will be operated when coil D is short-circuited. This is also the preferred method of adjusting interrupters A and B' when coil D has more ampere-turns than coil C'. When the ampere-turns are equal, interrupter B' would of necessity be farther from its magnet C' than interrupter A would be from its magnet D. When coil D has the greater number of ampere-turns, 65 this would not necessarily be true though in

the adjustment it is preferred to have it so. The source of energy used to energize the rail-circuit is of low voltage, the potential preferably not to exceed two volts. If too much current be used, a larger leakage across the rails will occur and interrupter B may be actuated when not designed. The potential should be sufficient to energize magnet D, so that it will positively operate interrupter A; but it should not be sufficient when D is in circuit to energize C' sufficiently to cause it to operate interrupter B'.

When an alternating electric current is employed to energize an electric circuit including electromagnets, the electrical resistance or impedance of that circuit will be considerably higher than when the same is excited by a continuous current. This is true of any alternating-current circuit; but its importance is particularly emphasized when such a current is sought to be used in the rail-circuit of a signaling-block, the varying and increased resistance being likely to prevent the signaling mechanism performing its proper functions. The rails of a signaling-block being practically grounded, a leakage of current is constantly taking place across them through the ground and ties. This leakage varies with the length of the block, the character of the soil and ties, the resistance of the rail-circuit, and the potential. Under ordinary conditions while using a continuous current in a rail-circuit it is necessary to make the blocks comparatively short. Under the same conditions when an alternating current is employed the block must be shorter or a greater waste of current will take place, rendering the signals uncertain. The increased resistance of a circuit having electromagnets due to the alternating current is technically known as a "spurious" resistance. It is this spurious resistance, no doubt, that has prevented the alternating current being practically and generally used in block-signaling. One of the objects of this invention is to minimize and substantially overcome the effect of the spurious resistance. This I do by winding the coils included in the rail-circuit with metallic tape instead of ordinary round wire and by connecting the coils in parallel with condensers of suitable capacity. The winding of the coils with metallic tape alone will greatly reduce the spurious resistance, and when they are so wound and connected with condensers, as stated, the spurious resistance will be reduced about ninety-nine per cent. and will become a negligible quantity in block-signaling. Each condenser so used to minimize the spurious resistance should have a faradic capacity suitable for the particular electromagnet in connection with which it is designed to be used. That capacity can be best found by trial, though there are formulas that may be found in technical works by means of which, with experimental data necessary to furnish the

means to calculate, the proper capacity may be mathematically determined. It is as difficult, however, to get the experimental data as it is to find the proper capacity of the condenser by trial.

In Fig. 1 the alternating current is shown as taken from an ordinary alternating-current power-circuit W X and its potential lowered by means of transforming-condensers PS ps, 10 the former supplying current to the signal and the latter to the rail circuit. A detailed description of these condensers is not here deemed essential, as they form in themselves no part of this invention. It is sufficient to 15 say of them that each transforming-condenser may be composed of two ordinary condensers. One, P, may be called the "primary" condenser and the other, S, the "secondary" condenser. The primary plates are connected to 20 the power-circuit in parallel and the secondary plates to the signal and rail circuits in series. In the construction of the transforming-condenser the primary plates are so arranged with reference to the secondary plates 25 as to charge them. The ratio of conversion is determined by the ratio of the area of the primary plates to that of the secondary plates, the former being the smaller for a step-down and the larger for a step-up transformation.

30 In practice any suitable electromagnetic device for operating the signals may be used, an ordinary solenoid being herein shown, the same being especially suitable for diagrammatic purposes. The plunger R is connected 35 to signal L by means of a rod or cable 90.

The rail-circuit is energized by a current from the source of energy s' , through wire h' , rail K' , wire v , coil D, wire x , rail J^2 , wire h' , coil C', wire l' , rail J^3 , and wire g' . The condenser m is connected in parallel to the terminals of coil D by wires w o . The condenser n' is similarly connected to the terminals of coil C' by wires i j . These condensers are being constantly charged by the current 45 from s' and are constantly discharging through coils C' and D. If a train enters block E, its wheels and axles will form a short circuit across the track-rails J K. The increased current that will thereby flow through 50 the rail-circuit will fully energize magnet C and cause it to operate circuit-interrupter B, which then makes electrical connection with contact-point c . If block F is now safe, magnet D will be energized and will be holding 55 interrupter A against contact-point f . The signal-circuit being thus completed, the current from the source S will flow through wire a , circuit-interrupter A, contact-point f , wire e , coil M, wire d , circuit-interrupter B, contact-point c , and wire b , completing the circuit. Solenoid M being energized, it draws 60 down its plunger R, which in turn draws signal L to a predetermined inclined position to indicate safety. If at the time contact is 65 made between B and c there is a train on block

F, short-circuiting the current from magnet D, the signal-circuit will be open between A and f , in which case the operation of circuit-interrupter B will have no effect on signal L, since the signal-circuit will not have been 70 completed.

If the trouble that caused magnet D to be deenergized be removed while a train is on block E, D will become energized and cause interrupter A to make electrical contact with point f , the signal-circuit being 75 thereby completed, and signal L will come to the position of safety, as described. The outgoing end of block E terminates at the insulation U, at which point block F commences, and it ends at insulation U' , comprising on 80 one side rails J' and J^2 and on the other side parts of rails K and K'. The distance between U and U' covered by rail J' is the overlapping portion of block E onto block F. It, in fact, forms a part of each block. When the 85 first pair of wheels passes onto the overlap, it forms a short circuit across the rails J' and K, thereby deenergizing magnet C, which allows circuit-interrupter B to fall by gravity from c , opening the signal-circuit, deenergizing M, and allowing signal L to resume the 90 position of danger, being sufficiently counterpoised to draw plunger R upward to normal position. The signal is preferably placed within block F a sufficient distance to enable 95 the engineer to see it resume the position of danger. When the first pair of wheels passes from rail J' onto rail J^2 , the current from the source of energy s' is short-circuited from magnet D, which allows interrupter A to 100 move by gravity from f , opening the circuit of signal L. Magnet C' now becomes fully 105 energized, as did magnet C when the train short-circuited rails J and K, the action already described being repeated for signal L'. Until the whole of the train passes off the overlap J^2 signal L cannot be brought to "safety," since the source of energy s' is being short-circuited from magnet D. As the train 110 is moving from rail J^2 onto J^4 it has two danger-signals behind it, L and L'. If it is desired to use distant signals, one may be connected in the signal-circuit of L' or L either in parallel or series, preferably the latter manner.

Referring to Fig. 2, H and H' are two iron or other suitable rods bolted at one end to the opposite track-rails, the other end of each rod being bent at an angle. The rods are placed in close proximity to each other and so held by suitable means. (Not shown.) The rods are adjusted so that the bent ends come within about one inch of each other, the angles being turned so as to engage each other when the track spreads one inch, thereby closing a 120 short circuit. The free ends may of course be adjusted to indicate the spreading of rails any distance. In addition to forming a short circuit across the rails the rods hold the rails 125 from spreading farther. The short circuit 130

formed by these rods has the same effect as though the short circuit were produced by a train located at the same point.

If it is desired that a train should lock a switch in advance of it when it enters a block and unlock the same after passing it, the same may be accomplished by using a suitable magnet in the rail-circuit that will operate a circuit-interrupter. This may be done by a magnet arranged to operate as C', though it is preferable to use a differential magnet, as V Y. Coil V is wound of very low resistance and connected by wires y and y' to one of the track-rails, one terminal to rail J' and the other terminal, y', to contact-point 10, with which switch-point J⁸ makes electrical contact, J⁸ making electrical connection with rail J⁶, which is in electrical connection with rail J' when the switch is set for the main track. Rails J⁷ and J⁹ are electrically insulated. Coil Y is wound to produce the same ampere-turns as coil V and is to be of very much higher resistance, preferably not less than fifty ohms. The terminals of this coil z z' are connected, respectively, to rails K² and J⁷, the current flowing through coil Y in the opposite direction to that which flows through V in order that the magnet V Y will be normally inactive. When a train enters this block, the coil Y is short-circuited and coil V operates circuit-interrupter Z, closing the local circuit through the source of energy 1, wire 2, electromagnet 3, wire 4, circuit-interrupter Z, and wire 5. Coil 3 operates lever 6, drawing its bent end into hole 7 in draw-bar 8, which is attached to the points of the switch or otherwise suitably located. This prevents the draw-bar being moved to open the switch. This form of lock has been illustrated because of its grammatic simplicity; but it will be understood that any suitable design of lock may be used. When the train passes the point where rails J⁹ and J⁷ are separated by insulation U⁵, coil V becomes short-circuited, Z falls by gravity from its anvil, the local circuit is opened, magnet 3 is deenergized, and retractile spring 9 raises lever 6, so that its bent end disengages hole 7 in draw-bar 8, thereby unlocking the switch. The continuity of electric connection from rail J' to rail J⁶ being through contact-point 10, if the switch is turned for the siding or not properly closed no current will flow, and the signal guarding the block cannot be brought to safety. The condenser 11 is connected to coil V in parallel and acts to reduce spurious resistance as described with reference to condensers m and n. A similar condenser is to be connected with all coils which are connected in series with the rails, so as to keep the resistance of the rail-circuit as low as possible.

The highway-gate 93 is counterpoised to be raised by gravity and arranged to be lowered by the action of an electric motor. (Not shown.) The motor is connected in a local

circuit having a suitable source of energy. The bell 12 may also be connected in the same local circuit, as shown, or in a separate circuit. When a bell is connected in circuit with other electroreceptive devices, it should be in a shunt. The local circuit in which the bell and the gate-operating mechanism are included is made and broken by circuit-interrupter Z', which is controlled by the differential electromagnet V' Y'. The coils of this magnet are wound and connected the same as those of magnet V Y, and its operation is the same. A like differential magnet, having one of its coils connected in series across insulated portions of one of the rails and the other coil connected in a shunt across the track-rails, may be used to operate circuit-interrupter 19, which short-circuits the rails to indicate burned culverts or bridges. When this is done, the fuse-wire y⁴ is connected in and forms part of the shunt across the rails. This fuse-wire may be connected with the timbers of a culvert or bridge in any suitable manner, such as winding it about the timbers or tacking it here and there on them. When this wire is placed on the structure and connected in circuit, the burning of the structure will fuse the wire, opening the circuit through the coil with which it is connected, which coil becoming deenergized destroys the differential condition of the magnet, allowing the other coil to operate the circuit-interrupter. In using this coil for that purpose it is evident that interrupter 19 will be actuated every time a train enters a block, because of the short-circuiting of the parallel coil. It is preferred, therefore, to use for this purpose magnet V² V³. (Shown in Fig. 2.) In using magnet V² V³ interrupter 19 will never be operated except when the structure guarded is burned or when the circuit through one of the coils is interrupted. Coils V² and V³ are each constructed of very low resistance, preferably not to exceed one-twentieth of one ohm. One of the coils V² has one of its terminals connected to rail J⁴ and the other to one end of the fuse-wire y⁴, the other end of the fuse-wire being connected to rail J⁵, which is separated from rail J⁴ by insulation U³. Coils V² and V³ are connected in circuit, so that the current will flow through them in opposite directions, the coils being wound for the same ampere-turns. It is not essential that coil V², which is connected with the fuse-wire, should be of low resistance; but it is preferable to so have it. The resistance of the fuse-wire may be considerable, depending on the kind, size, and amount used. This resistance, however, will not materially alter that of the rail-circuit, since the total resistance across insulation U³ will be less when coils V² and V³ are connected than when either of them is alone connected. When the fuse-wire y⁴ is destroyed by fire or otherwise, coil V² will be deenergized and coil V³ will operate interrupter 19, 130

which is electrically connected to one of the track-rails by wire y^6 , its anvil 20 being connected to the other track-rail by wire 21. When interrupter 19 makes electrical connection with anvil 20, the track-rails will be short-circuited and the signal governing the block and any device within the block will be affected the same as though the short circuit was caused by a train. A condenser is designed to be connected with each of the coils V^2 and V^3 .

The magnets V^Y and $V^2 V^3$ may be used when wound and connected substantially as shown and described for the performance of other functions in block-signaling.

When it is desired to communicate the condition of a signal to an approaching train automatically or to automatically stop it if it violates such a signal, the same is done as follows, reference being specially made to Fig. 3: The action of signal L^2 is the same as already described with reference to signals L and L' , and that action will not be here repeated except that, as shown in Fig. 3, the source of energy that energizes the signal-circuit is from the secondary coil of an ordinary alternating-current transformer. The source might be a transforming-condenser or a primary or secondary battery. In order to communicate signals to a train or stop it, one side or terminal of the source of energy 24 is normally connected by wire b^2 , wires 25 26 to contact-rail N and by wires b^2 25 29, coil 30, and wire 31 to emergency-rail O. The other side or terminal of the source of energy is normally connected to interrupter A^2 . Stop 22 is normally connected by wire 23 to track-rail K^2 . When interrupter A^2 breaks contact with its anvil or stop f^2 , as before explained with reference to A and A' , it falls by gravity onto and makes electrical contact with stop 22, thereby connecting one terminal of the source of energy used in the signal-circuit to one of the track-rails. On the engine or some other place on a train is located a suitable contact-brush 32, which is electrically insulated from the metal of the engine or other metal that comes in contact with the wheels or axles of the train. A partial circuit is made on the train through suitable electroreceptive devices from brush 32 to wheels and axles 52. A contact or caution rail N is located on the road-bed at about the place where a distant signal would be placed were one used. It is so situated that brush 32 will engage it when the train is passing. This contact-rail has portions of its surface covered by electrical insulators Q, Q' to cause interruptions in the current that energizes the electroreceptive devices on the train, they being particularly intended to enable the steam-whistle to give certain predetermined blasts to call the attention of workmen to the position of the signal in order that if due to carelessness the trouble may be removed be-

fore the train is stopped. In the illustration the electroreceptive devices shown on the train connected with brush 32 and wheels and axles 52 are a gong 51, an electric lamp 42, and electromagnet 43, intended to operate 70 air-valve 44, which will allow air to slowly escape from air-pipe 45, that is suitably connected with the air-brake system, and an electromagnet 47, which is designed to pull lever 48 of steam-whistle 49, the retractile spring 75 50 restoring the lever to its normal position when the pull of magnet 47 ceases. When brush 32 comes in contact with rail N and interrupter A^2 is in contact with stop 22, an electric circuit will be completed from the source 80 of energy 24 through wires b^2 25 26, rail N, brush 32, wire 33, the various electroreceptive devices, as shown, to wire 55, wheel 52, rail K^2 , wire 23, stop 22, interrupter A^2 , and wire a^2 , completing the circuit and operating the 85 various electroreceptive devices as stated, the steam - whistle receiving as many interruptions as there are insulators on rail N. To stop the train when a danger-signal is violated, another partial circuit is used on the 90 train composed of contact-brush 62, wires 63 73, coil 65, wires 66 64, coil 67, wires 75 68, coil 69, wire 70, and wheel 71. Contact-brush 62 is electrically insulated from the metal-work of the engine and is so located as 95 to engage rail O, but not to engage rail N. Contact-rail O is located on the road-bed just within block H^2 —that is, just within the block governed by signal L^2 . It may of course be placed within block G, but when so placed 100 compels a train to stop before reaching the signal, thereby interrupting trains when it may not be necessary for them to stop. When no overlaps are used, this rail should be placed within block G, between rail N and the outgoing end of the block. This rail is connected with one terminal of the source of energy 24 by wires b^2 25 29, coil 30, and wire 31. The other terminal of the source of energy is connected to interrupter A^2 , as before stated. If 105 brush 62 comes into contact with rail O while interrupter A^2 is in electrical connection with stop 22, an electric current will flow from the source of energy 24 through wires b^2 25 29, coil 30, wire 31, contact-rail O, brush 62, and 110 wire 63 to point 72. Here it divides, one portion going through wire 73, coil 65, and wire 66 to point 74. The other portion flows from point 72 through wire 64, coil 67, and wire 75 to point 74, where the portions unite and 115 complete the circuit through wire 68, coil 69, wire 70, wheel 71, rail K^2 , wire 23, stop 22, interrupter A^2 , and wire a^2 to the source of energy. Solenoids 30 and 69 operate registers 76 and 77, respectively. Solenoids 65 120 and 67 operate air-valves 59 and 58, respectively. These valves may be of any suitable design, though partially - balanced rotary valves are preferred. Plunger 78 is connected with valve 58 by cable 79. When plunger 125 130

78 is drawn into solenoid 67, valve 58 is rotated until port 80 assumes a position through which the air in pipe 81 may exhaust. The arrangement and operation of all the air-valves shown is the same, except that valve 44 has a small port in order that the air may escape slowly. The solenoids 65 and 67 are preferably connected in parallel, as shown, though they may be connected in series. The object in having two emergency-valves is to increase the certainty of operation.

Special attention is directed to the fact that if signal L^2 is at "safety" when the train passes from block G onto block H² the emergency-valves 65 and 67 will not be operated notwithstanding signal L^2 comes to "danger" while brush 62 is on rail O. The explanation of this is that signal L^2 at this time comes to "danger" by virtue of interrupter B² opening the circuit. Magnet D² is still energized and no contact is made between interrupter A² and stop 22.

It is possible for all electrical contacts to become defective through negligence or inattention. To guard against trouble because of such defect, an additional electrical path from wire a^2 to wire 23 is provided. This is shown in Fig. 3, where wire 81 connects wire a^2 with interrupter 82, which is normally held open against stop 85. Wire v^2 may be divided and connected to the terminals of coil 84, in which case the resistance of coil 84 should be very low. It is preferred, however, in order to avoid any increase in the resistance of the rail-circuit to wind coil 84 of high resistance as compared with the series coils and to connect it in parallel. This connection is shown in Fig. 3, where wires 87 and 88 are connected, respectively, with wires x^2 and v^2 . When coil D² is energized, coil 84 will be, and when it is deenergized coil 84 will be deenergized, so that when interrupter A² rests on stop 22 interrupter 82 will rest on stop 86, which is connected by wire 83 to wire 23.

By the term "electrically-controlled device" I refer to means under the control of the rail-circuit and employed to control the circuit in which the signal is placed. As illustrated by the drawings in this instance, the same consists of an electromagnet connected to the track-rails and a circuit-interrupter included in the signal-circuit, the magnet operating the interrupter. When the magnet is sufficiently energized to actuate the interrupter, I consider the device energized. When it is insufficiently energized to operate the interrupter, I consider it deenergized, whether the magnet be partially or entirely demagnetized. As means other than the magnet and interrupter may be employed for the purpose stated, I consider as within the meaning of the term any equivalent means or any means that will readily suggest itself to one skilled in the art, and especially any means that absorbs electric energy from the rail-circuit and translates it

into mechanical movements in the signal-circuit.

Having now described my invention, what I claim as new, and desire to secure by Letters Patent, is—

1. In a rail-circuit, the combination of a source of alternating electric energy, situated at the outgoing end of a block, the track-rails of a signaling-block, two electromagnets, one of said magnets being located at the outgoing end of the block and the other at the incoming end of the block, and two condensers, one pole of said source of energy being connected to the outgoing end of one of the track-rails, the other pole of said source of energy being electrically connected to one terminal of the magnet situated at the outgoing end of the block, the other terminal of said magnet so situated at the outgoing end of the block being connected to the other track-rails at the outgoing end of the block; the electromagnet located at the incoming end of the block having its terminals connected to the incoming ends of the track-rails; one of said condensers being connected in parallel to the terminals of the magnet located at the outgoing end of the block, and the other condenser being connected in parallel to the terminals of the magnet located at the incoming end of the block; the magnet at the outgoing end of the block being suitably arranged to exert insufficient attraction upon its armature to actuate it, while the magnet at the incoming end of the block is sufficiently energized to operate its armature. 75

2. In a rail-circuit, the combination of a source of alternating electric energy situated at the outgoing end of the block, the track-rails of a signaling-block, two electromagnets, one of said magnets being located at the outgoing end of the block and the other at the incoming end of the block, and a condenser; one pole of said source of energy being connected to the outgoing end of one of the track-rails, the other pole of said source of energy being electrically connected to one terminal of the magnet situated at the outgoing end of the block, the other terminal of said magnet so situated at the outgoing end of the block being connected to the outgoing end of the other track-rail; the electromagnet located at the incoming end of the block having its terminals connected to the incoming ends of said track-rails; the said condenser being connected in parallel with the terminals of the magnet situated at the outgoing end of the block; the magnet at the outgoing end of the block being suitably arranged to exert insufficient attraction upon its armature to actuate it while the magnet at the incoming end of the block is sufficiently energized to operate its armature. 100

3. In a rail-circuit, the combination of a source of alternating electric energy situated at the outgoing end of the block, the track-rails of a signaling-block, two electromagnets, one of said magnets being located at the out- 105 110 115 120 125 130

going end of the block and the other at the incoming end of the block, and a condenser; one pole of said source of energy being connected to the outgoing end of one of said track-rails, 5 the other pole of said source of energy being electrically connected to one terminal of the magnet situated at the outgoing end of the block, the other terminal of said magnet being connected to the outgoing end of the other track-rail; the electromagnet located at the incoming end of the block having its terminals connected to the incoming ends of said track-rails; the said condenser being connected in parallel to the terminals of the magnet located 10 at the incoming end of the block; the magnet at the outgoing end of the block being suitably arranged to exert insufficient attraction upon its armature to actuate it while the magnet at the incoming end of the block is sufficiently energized to operate its armature. 15

4. In a rail-circuit, the combination of a source of alternating electric energy situated at the outgoing end of the block, the track-rails of a signaling-block, two electromagnets, 20 one of said magnets being located at the outgoing end of the block and the other being located at the incoming end of the block, the helix of the magnet located at the outgoing end of the block being composed of metallic tape, and a 25 condenser; one pole of said source of energy being connected to the outgoing end of one of the track-rails, the other pole of said source of energy being electrically connected to one terminal of the magnet situated at the outgoing end of the block, the other terminal of said 30 magnet so situated at the outgoing end of the block being connected to the outgoing end of the other track-rail; the electromagnet located at the incoming end of the block having its 35 terminals connected to the incoming ends of said track-rails; the said condenser being connected in parallel with the terminals of the magnet at the incoming end of the block; the magnet at the outgoing end of the block being 40 suitably arranged to exert insufficient attraction upon its armature to actuate it while the magnet at the incoming end of the block is sufficiently energized to operate its armature. 45

5. In a rail-circuit, the combination of a source of alternating electric energy situated at the outgoing end of the block, the track-rails of a signaling-block, two electromagnets, 50 one of said electromagnets being located at the outgoing end of the block and the other at the incoming end of the block, the helix of said magnet so situated at the incoming end of the block being composed of metallic tape, and a condenser; one pole of said source of energy being connected to the outgoing end of one of 55 said track-rails, the other pole of said source of energy being connected electrically to one terminal of the magnet so situated at the outgoing end of the block, the other terminal of said magnet so situated at the outgoing end 60 of the block being connected to the outgoing 65

end of the other track-rail; the electromagnet located at the incoming end of the block having its terminals connected to the incoming ends of said track-rails; the said condenser being connected in parallel to the terminals of the magnet at the incoming end of the block; the magnet at the outgoing end of the block being suitably arranged to exert insufficient attraction upon its armature to actuate it while the magnet at the incoming end of the block is sufficiently energized to operate its armature. 70

6. In a rail-circuit, the combination of a source of electric energy situated at the outgoing end of a signaling-block; the track-rails of a signaling-block, said rails extending into the block next in advance a sufficient distance to form an overlap, one of the said rails being electrically continuous from the incoming end of the block, or from the termination of an overlap at the incoming end of the block, to 80 the end of the overlap at the outgoing end of the block, the other rail being electrically separated into two portions, one of the portions extending from the incoming end of the block, or from the termination of an overlap at the incoming end of the block, to the outgoing end of the block, and the other portion extending from the outgoing end of the block to the termination of the overlap at the outgoing end of the block; and two electromagnets, one of said 85 electromagnets being located at the outgoing end of the block and the other at the incoming end of the block; the source of energy being connected to said track-rails at the termination of the overlap formed at the outgoing 90 end of the block; the magnet at the outgoing end of the block being connected to the track-rail electrically insulated at the outgoing end of the block, one terminal of said magnet being connected to the beginning of the overlapping rail, the other terminal of said magnet being connected to the end of the track-rail so insulated at the outgoing end of the block; the terminals of the electromagnet at 95 the incoming end of the block being connected to the ends of the track-rails at the incoming end of the block; the magnet at the outgoing end of the block being suitably arranged 100 to exert insufficient attraction upon its armature to actuate it while the magnet at the incoming end of the block is sufficiently energized to operate its armature. 105

7. In a rail-circuit, the combination of a source of alternating electric energy situated at the outgoing end of the signaling-block; the track-rails of a signaling-block, said rails extending into the block next in advance a sufficient distance to form an overlap, one of said rails being electrically continuous from the incoming end of the block, or from the termination of an overlap at the incoming end of the block, to the termination of the overlap at the outgoing end of the block, the other rail being electrically separated into two portions, 110 one of the portions being electrically continuous 115

ous from the incoming end of the block, or from the termination of an overlap at the incoming end of the block, to the outgoing end of the block, the other portion of said rail being electrically continuous from the termination of the first portion of said rail to the termination of the overlap at the outgoing end of the block; two electromagnets, one of said magnets being situated at the outgoing end of the block and the other at the incoming end of the block; and two condensers; the source of energy being connected to said track-rails at the termination of the overlap formed at the outgoing end of the block; the electromagnet located at the outgoing end of the block being connected to the track-rail electrically divided at the outgoing end of the block, one terminal of said magnet being connected to the beginning of the overlapping portion of said track-rail, the other terminal of said magnet being connected to the outgoing end of the first portion of said divided track-rail; the terminals of the electromagnet at the incoming end of the block being connected to the ends of the track-rails at the incoming end of the block; the said condenser being connected in parallel to the terminals of the magnet at the outgoing end of the block; the magnet at the outgoing end of the block being suitably arranged to exert insufficient attraction upon its armature to actuate it while the magnet at the incoming end of the block is sufficiently energized to operate its armature.

8. In an electric rail-circuit, the combination of a source of alternating electric energy situated at the outgoing end of a signaling-block; the track-rails of a signaling-block, said rails extending from the incoming end of the block, or from an overlap at the incoming end of the block, into the block next in advance a sufficient distance to form an overlap, one of said rails being electrically continuous from the incoming end of the block, or from the termination of an overlap at the incoming end of the block, to the termination of the overlap formed by the extended rails at the outgoing end of the block, the other track-rail being electrically separated into two portions, one of the portions being electrically continuous from the incoming end of the block or from the termination of an overlap at the incoming end of the block, to the outgoing end of the block, the other portion of said rail being electrically continuous from the termination of the first portion to the termination of the overlap at the outgoing end of the block; two electromagnets, one of said magnets being located at the outgoing end of the block and the other at the incoming end of the block; and a condenser; the source of energy being connected to said track-rails at the termination of the overlap formed by the extended rails at the outgoing end of the block; the electromagnet at the outgoing end of the block being connected to the track-rail electrically divided at the outgoing end of the block, one terminal of said magnet being connected to the beginning of the overlapping portion of said track-rail, the other terminal of said magnet being connected to the outgoing end of the first portion of said track-rail; the terminals of the magnet at the incoming end of the block being connected to the ends of the track-rails at the incoming end of the block; the said condenser being connected in parallel to the terminals of the magnet at the incoming end of the block; the magnet at the outgoing end of the block being suitably arranged to exert insufficient attraction upon its armature to actuate it while the magnet at the incoming end of the block is sufficiently energized to operate its armature.

outgoing end of the block; the electromagnet at the outgoing end of the block being connected to the track-rail electrically divided at the outgoing end of the block, one terminal of said magnet being connected to the beginning of the overlapping portion of said track-rail, the other terminal of said magnet being connected to the outgoing end of the first portion of said divided track-rail; the terminals of the electromagnet at the incoming end of the block being connected to the ends of the track-rails at the incoming end of the block; the said condenser being connected in parallel to the terminals of the magnet at the outgoing end of the block; the magnet at the outgoing end of the block being suitably arranged to exert insufficient attraction upon its armature to actuate it while the magnet at the incoming end of the block is sufficiently energized to operate its armature.

9. In an electric rail-circuit, the combination of a source of alternating electric energy situated at the outgoing end of a signaling-block; the track-rails of a signaling-block, said rails extending from the incoming end of the block, or from an overlap at the incoming end of the block, into the block next in advance a sufficient distance to form an overlap, one of said rails being electrically continuous from the incoming end of the block, or from the termination of an overlap at the incoming end of the block, to the termination of the overlap formed by the extended rails at the outgoing end of the block, the other track-rail being electrically separated into two portions, one of the portions being electrically continuous from the incoming end of the block or from the termination of an overlap at the incoming end of the block to the outgoing end of the block, the other portion of said rail being electrically continuous from the first portion of said rail to the termination of the overlap at the outgoing end of the block; two electromagnets, one of said magnets being located at the outgoing end of the block and the other at the incoming end of the block; and a condenser; the source of energy being connected to said track-rails at the termination of the overlap formed by the extended rails at the outgoing end of the block; the electromagnet at the outgoing end of the block being connected to the track-rail electrically divided at the outgoing end of the block, one terminal of said magnet being connected to the beginning of the overlapping portion of said track-rail, the other terminal of said magnet being connected to the outgoing end of the first portion of said track-rail; the terminals of the magnet at the incoming end of the block being connected to the ends of the track-rails at the incoming end of the block; the said condenser being connected in parallel to the terminals of the magnet at the incoming end of the block; the magnet at the outgoing end of the block being suitably arranged to exert insufficient attraction upon its armature to actuate it while the magnet at the incoming end of the block is sufficiently energized to operate its armature.

- sufficient attraction upon its armature to actuate it while the magnet at the incoming end of the block is sufficiently energized to operate its armature.
- 5 10. The combination of a signal-circuit having a suitable source of electric energy, electromagnetic signal-actuating mechanism and two circuit-interrupters with the normally closed rail-circuits of two abutting signaling-blocks, the rail-circuit of one of said blocks having an electromagnet situated at the incoming end of said signaling-block adapted to hold one of the circuit-interrupters in said signal-circuit normally closed, the rail-circuit of the other of said abutting blocks having an electromagnet situated at the outgoing end of said block and adapted on being sufficiently energized to close the other of the circuit-interrupters included in said signal-circuit.
- 15 11. In an electric signaling system, the combination of a normally open signal-circuit including two circuit-interrupters; a normally closed track-circuit having a source of energy, the track-rails of the entire signaling-block and two electromagnets, one located at the incoming end of the block and the other at the outgoing end of the block, all connected in series, the magnet at the incoming end of the block being arranged to control and hold normally closed one of the circuit-interrupters in said signal-circuit; and a second normally closed track-circuit having a source of energy, the track-rails of the entire block and two electromagnets, one of said magnets being located at the incoming end of said block and the other at the outgoing end of said block, all connected in series, the magnet at the outgoing end of said block being constructed, and adjusted with reference to its armature-lever, so that it will normally be incapable of attracting its armature and arranged to control the other circuit-interrupter included in said signal-circuit, the said circuit-interrupter so controlled by the magnet at the outgoing end of the block being held normally open by gravity.
- 20 12. The combination of a signal-circuit having a source of electric energy, electromagnetic signal-actuating mechanism and two circuit-interrupters, one of said circuit-interrupters being connected to one pole of the source of energy, the other circuit-interrupter being connected to one terminal of the electromagnetic signaling mechanism, the other pole of the source of energy being connected to a contact-point adapted to engage the circuit-interrupter connected to the electromagnetic signal-actuating mechanism, the other terminal of the electromagnetic signal-actuating mechanism being connected to a contact-point adapted to be engaged by the circuit-interrupter connected to said source of energy, with the rail-circuits of two abutting signaling-blocks, the rail-circuit of one of said blocks having an electromagnet situated at the in-
- coming end of the said block adapted to control the circuit-interrupter in the signal-circuit which is connected with one pole of the source of energy, the rail-circuit of the other of said abutting blocks having an electromagnet situated at the outgoing end of said abutting signaling-block connected in series with the source of energy, the track-rails and a magnet situated at the incoming end of said block, and adapted to control the circuit-interrupter in the signal-circuit which is connected to one terminal of the electromagnetic signal-actuating mechanism.
- 25 13. The combination of a source of electric energy employed in energizing a local signal-circuit and situated at the abutting ends of two signaling-blocks, a circuit-interrupter included in said signal-circuit and directly connected through a suitable conductor with one pole of said source of energy, an electromagnet arranged to control said circuit-interrupter and included in the rail-circuit of the advanced one of said abutting blocks, the terminals of said magnet being connected to the track-rails at the incoming end of said advanced block, an electric conductor connected with one of the track-rails in the rear one of said abutting blocks and arranged to make electrical connection with the circuit-interrupter when the magnet controlling said interrupter is deenergized, a contact-rail situated on the bed of the railway and directly connected through a suitable conductor with the pole of the source of energy not connected to the circuit-interrupter, a partial electric circuit located on a railway-vehicle including an electromagnet, and an air-valve connected with an air-brake system on said vehicle, said valve being controlled by said magnet in said partial circuit, one terminal of the partial circuit on said vehicle being connected to an insulated contact-brush arranged to engage the contact-rail on the road-bed, the other terminal of said partial circuit being connected to the wheels and axles of said vehicle whereby on said contact-brush engaging said contact-rail while the electromagnet controlling the circuit-interrupter is demagnetized, the full force of the source of energy of said signal-circuit will be utilized in energizing said partial circuit, substantially as shown and described.
- 30 14. The combination of a source of energy employed in energizing a local signal-circuit located at the abutting ends of two signaling-blocks, a circuit-interrupter included in said signal-circuit and directly connected through a suitable electric conductor with one pole of said source of energy, an electromagnet arranged to actuate the circuit-interrupter and controlled by the rail-circuit of the advanced one of said abutting blocks, an electric conductor connected with the track-rail of the rear one of said abutting blocks and arranged to make electrical contact with the circuit-in-

terrupter when the magnet controlling said interrupter is deenergized, a contact-rail situated on the road-bed and within the overlap that is formed by the rear one of said abutting blocks extending into the advanced block, said contact-rail being directly connected with the pole of the source of energy not connected to said interrupter, and a partial electric circuit located on a railway-vehicle and containing electroreceptive devices, one of the terminals of said partial circuit being connected to a contact-brush, insulated from said vehicle and arranged to engage the said contact-rail so located on the road-bed, the other terminal of said partial circuit being connected to the wheels and axles of said vehicle, substantially as shown and described.

15. The combination of a source of electric energy employed in energizing a local signal-circuit situated at the abutting ends of two signaling-blocks, two circuit-interrupters directly connected through suitable conductors with one pole of the source of energy, one of said interrupters being included in the signal-circuit, two electromagnets arranged to actuate said interrupters and controlled by the rail-circuit of the advanced one of the two abutting blocks, an electric conductor connected with the track-rail of the rear one of said abutting blocks and arranged to make electrical contact with the circuit-interrupters when the magnets controlling said interrupters are deenergized, a contact-rail situated on the road-bed and electrically connected with the pole of the source of energy not connected to the circuit-interrupters, and a partial electric circuit located on a railway-vehicle containing electroreceptive devices and having one terminal connected to an insulated contact-brush arranged to engage the contact-rail on the road-bed, the other terminal being connected to the wheels and axles of said vehicle, substantially as shown and described.

16. The combination of a source of electric energy employed in energizing a local signal-circuit situated at the abutting ends of two signaling-blocks, two circuit-interrupters directly connected through suitable electric conductors with one pole of the source of energy, one of said interrupters being included in the signal-circuit, two electromagnets arranged to actuate said interrupters and controlled by the rail-circuit of the advanced one of said abutting blocks, one of said magnets being connected in series and the other in parallel with the track-rails of said advanced one of the abutting blocks, an electric conductor connected with the track-rail of the rear one of said abutting blocks and arranged to make electrical contact with the circuit-interrupters when the magnets controlling said interrupters are deenergized, a contact-rail situated on the road-bed and electrically connected with the pole of the source of energy not connected to said interrupters, and a partial elec-

tric circuit located on a railway-vehicle containing electroreceptive devices and having one terminal connected to an insulated contact-brush arranged to engage the contact-rail on the road-bed, the other terminal being connected to the wheels and axles of said vehicle, substantially as shown and described.

17. The combination of a source of electric energy, a circuit-interrupter connected to one pole of the source of energy, an electromagnet arranged to actuate said interrupter and controlled by the rail-circuit of the advanced one of two abutting blocks, an electric conductor connected to the track-rail of the rear one of two abutting blocks and arranged to make electrical contact with the circuit-interrupter when the magnet controlling said interrupter is deenergized, a contact-rail connected with the pole of the source of energy not connected to said interrupter, said contact-rail having its surface divided into electrically conducting and non-electrically conducting portions, a partial electric circuit located on a railway-vehicle including electroreceptive devices, one of the terminals of said partial circuit being connected to an insulated contact-brush arranged to engage said contact-rail, the other terminal of said partial circuit being connected to the wheels and axles, and the steam-whistle of a locomotive, substantially as shown and described.

18. The combination of the rail-circuit of a signaling-block, a differential electromagnet having a low-resistance coil the terminals of which are connected to insulated portions of, and in series with, one of the track-rails, and a higher-resistance coil connected in parallel with the track-rails, said differential magnet being located at a point between the ends of a signaling-block, a local circuit including an electromagnet and a circuit-interrupter under the control of said differential magnet, and switch-locking mechanism under the control of the electromagnet in said local circuit, substantially as shown and described.

19. The combination of the rail-circuit of a signaling-block, a differential electromagnet having a low-resistance coil the terminals of which are connected to insulated portions of and in series with one of the track-rails and a higher-resistance coil connected in parallel with the track-rails, a local circuit including an electric motor and a circuit-interrupter under the control of said differential magnet, and a highway-crossing gate, said gate being counterpoised to remain normally open, substantially as shown and described.

20. The combination of the rail-circuit of a signaling-block, a differential electromagnet having a low-resistance coil the terminals of which are connected to insulated portions of and in series with one of the track-rails and a higher-resistance coil connected in parallel with the track-rails, a local circuit including

an alarm-bell and a circuit-interrupter under the control of said differential magnet, substantially as shown and described.

21. The combination of the rail-circuit of a 5 signaling-block, and a differential electromagnet located between the ends of a signaling-block and adapted to control signaling mechanism within said block, said magnet having a low-resistance coil connected to insulated portions of and in series with one of the track-rails and a higher-resistance coil connected in parallel with the track-rails, substantially as shown and described.

22. The combination of the rail-circuit of a 15 signaling-block, a differential electromagnet located between the ends of a signaling-block and adapted to control signaling mechanism within said block, said magnet having a low-resistance coil connected to insulated portions of and in series with one of the track-rails, also a higher-resistance coil connected in parallel with the track-rails, and a condenser connected in parallel to the terminals of said low-resistance coil, substantially as 20 shown and described.

23. The combination of the rail-circuit of a signaling-block, a differential electromagnet having a low-resistance coil the terminals of which are connected to insulated portions of 30 and in series with one of the track-rails, also a second coil included in a shunt-circuit the terminals of which shunt-circuit are connected to insulated portions of and in series with one of the track-rails, and a condenser connected 35 in parallel to the terminals of the coil not included in said shunt-circuit, substantially as shown and described.

24. The combination of the rail-circuit of a signaling-block, and a differential electromagnet 40 not having a low-resistance coil the terminals of which are connected to insulated portions of and in series with one of the track-rails, also a second coil included in a shunt-circuit the terminals of which circuit are connected 45 to insulated portions of and in series with one of the track-rails, said differential magnet being adapted to control signaling mechanism within said block, substantially as shown and described.

50 25. The combination of the rail-circuit of a signaling-block, a differential electromagnet

having a low-resistance coil the terminals of which are connected to insulated portions of and in series with one of the track-rails also a second coil included in a shunt-circuit the 55 terminals of which shunt-circuit are connected to insulated portions of and in series with one of the track-rails, said differential magnet being adapted to control signaling mechanism within said block, a railway-bridge or other 60 structure upon and about which the said shunt-circuit is suitably placed, and a normally open, low-resistance shunt-circuit including a circuit-interrupter, the terminals of which shunt-circuit are connected to the opposite track-rails, the circuit-interrupter included in said 65 last-mentioned circuit being under the control of said differential magnet, substantially as shown and described.

26. In railway signaling, the combination 70 of the track-rails of a signaling-block, said rails forming a portion of the rail-circuit of such signaling-block, and two rods, one end of each of said rods being bent at an angle and the other end of each of said rods being 75 suitably bolted to the opposite track-rails, the ends of said rods bent at an angle being arranged to engage each other on the spreading of said track-rails, substantially as shown and described.

27. A railway signaling system consisting of the combination of a consecutive number of closed-circuited track-sections, signals properly located for indicating the condition of an advance section, a source of energy in 80 circuit with each signal for actuating the same, two electrically-controlled devices connected with the rails of adjoining track-sections for controlling each signal-circuit, one of said devices being normally energized and the other 85 of said devices being normally deenergized, and a source of electrical energy so connected to each track-section that the entrance of a train on a section preceding the signal will cause the normally deenergized device of said 90 section to become energized, and with the normally energized device of the advance section to operate the signal of the advance section.
